UNITED STATES PATENT OFFICE.

EMILE FRANCKAERTS, OF SAN FRANCISCO, CALIFORNIA.

CHECK-HINGE.

1,393,889.

Specification of Letters Patent. Patented Oct. 18, 1921.

Application filed April 22, 1919, Serial No. 291,910. Renewed July 18, 1921. Serial No. 485,788.

To all whom it may concern:

Be it known that I, EMILE FRANCKAERTS, a citizen of the United States, residing at San Francisco, in the county of San Francisco and State of California, have invented new and useful Improvements in Check-Hinges, of which the following is a specification.

The present invention relates to an improved check-hinge, that is, a hinge which is associated with a spring for closing the door, and which is provided with cushioning means for preventing the door from being closed violently by the spring. The object 10 of the invention is to provide a check-hinge so constructed that the mechanism for closing the door will be contained in as small a space as possible, thereby reducing the size of the check-hinge; which will be provided 15 with means whereby the speed of the door may be varied and the door may be closed through one part of its angular movement at one speed and through the remaining part at a different speed; which will also be provided 20 with means whereby the door may be automatically held open at a certain angle, and one in which the parts may be as compact and as symmetrical in form as possible.

Other advantages of the invention will 30 appear from the detailed description thereof, and will be particularly pointed out in the claims.

In the accompanying drawing, Figure 1 is a front view of the check-hinge and portions of the door and door jamb in the closed position of the former; Fig. 2 is a vertical section on the line 2—2 of Fig. 4; Fig. 3 is a broken plan view of the door and check 35 hinge, the door being closed; Fig. 3^a is a view, similar to Fig. 3, of a modified form of the invention; Fig. 4 is a horizontal section on the line 4—4 of Fig. 2; Fig. 5 is a horizontal section on the line 5—5 of Fig. 40 10; Fig. 6 is an enlarged vertical section of a plunger; Fig. 7 is a plan view of a washer used in conjunction with said plunger; Fig. 8 is a view of one side of the check-hinge and the parts adjacent thereto, the door 45 being open; Fig. 9 is a view of the other side thereof, the check-hinge being detached from the door and jamb; Fig. 10 is a vertical section of the hinge in the position 50 shown in Fig. 8; Fig. 11 is a side view of a 55 plunger rod and plunger, detached.

Referring to the drawing 1 (Fig. 8) indicates a hinge leaf adapted to be secured by screws to the hinged edge of a door 2, and 3 indicates a companion hinge leaf adapted to be similarly secured to an adjacent surface of the door jamb 4, said edge and surface being recessed, as clearly shown at 5 in Fig. 3, to receive said hinge leaves. The hinge leaf 3 has at its top and bottom in planes at right angles thereto plate-like extensions 60 6, 7, having registering apertures in which are received unthreaded portions of the stems of screws 8, 9, screwed respectively into a cap 10 and a foot 11, both the cap 10 and the foot 11 having in their sides a circular series of radially extending sockets 12 to receive the end of an instrument for turning them, for a reason which will hereinafter appear. Around a reduced portion of the foot 11 can rotate a spring housing 13, in 70 which is contained a watch spring 14, of which the outer end is bent out at right angles, as shown at 15, and fitted in a vertical groove in the housing, and the inner end is bent inwardly at right angles, as shown 75 at 16, and fitted in a vertical groove in a vertical stem 18, extending upwardly from the center of the foot 11. Screwed into the upper end of said housing is the lower end of a casing 19, and 80 screwed into said lower end is a lower head 21 which has in its under side a central socket 22 to receive the reduced upper end of said stem 18. Thus said stem 18 and foot 11 can turn relatively to said casing 19, 85 head 21, and housing 13. Fitting into the upper end of said casing is an upper head 23 and rotatable upon said upper head 23 is a sleeve 24 having near its lower end an outwardly extending circular flange 26. Surrounding and screwed to the upper end of 90 said casing 19 and upper head 23, and secured thereto by a screw 27, is a sleeve 29 having a flange 31 extending inwardly over the flange 26, and retaining it in place. Fiber washers 25, 30 are interposed between the sleeve 24 and the head 23 and the casing 19 respectively. Surrounding the upper portion of said sleeve 24 is an upper spring 95 housing 32 secured thereto by a screw 33, 100 the upper part of which housing surrounds the cap 10, said upper part being recessed internally and containing a fiber ring 35 around said cap 10.

Said housing 32 is caused to rotate with 110

the door by means of a screw 34, which is screwed through a round extension 36, (Figs. 1, 5, 9,) of the hinge leaf 3 closely surrounding the housings 32 and 13, the 5 inner end of which screw 34 enters a socket 37 in said housing 32 and in the sleeve 24. The cap 10 is, however, held stationary with the hinge leaf 3 by means of a screw 38 entering one of the sockets 12 in said cap, 10 and screwed through a cylindrical extension depending from, and formed integral with, a plate 41, having a central aperture, through which, as well as through the aperture in the plate 6, the screw 8 extends, 15 said plate 41 having an extension 42 in a plane at right angles to that of the plate 41 and which is secured by screws to the door jamb in like manner with the hinge leaf 1, thus forming a hinge leaf supplementary to 20 the hinge leaf 1. The purpose of the cap 10, and of the means, comprising the parts 38, 41, 42, for securing it to the door jamb, is to furnish a support for one end of a 25 vertically disposed helical spring 43, contained within the spring housing 32. Its lower portion surrounds an upper portion, reduced in diameter, of the sleeve 24 while its upper end surrounds a reduced depending portion 44 of said cap 10, the ends of 30 said spring being received in notches 46 and 47, respectively, in said cap 10 and in a flange 48 extending inwardly from said spring housing 32.

Such being the construction of the parts 35 which cause the door to close automatically, the following is the mode of operation.

When the door is opened and the hinge leaves are separated from the position shown in Fig. 2, in which they are adjacent to one 40 another, to the position, for instance, shown in Figs. 5 and 10, in which they extend in planes parallel with each other, in which case the door has been swung through two right angles, the opening of the door will 45 have wound up both the upper spring 43 and the lower spring 14, the lower end of the upper spring and the outer end of the lower spring remaining stationary with the door jamb, and the upper end of the upper 50 spring and the inner end of the lower spring rotating about their common axis through two right angles. Then, when the door is released, the force thus imparted to the spring closes the door. The spring 43 can 55 be conveniently wound to any degree of tension by first unscrewing the screw 38 out of its socket 12, then turning the cap, and then screwing the screw 38 into another socket 12.

I will now describe the provision which 60 I make for cushioning the closure of the door.

Through said sleeve 24 and through the upper head 23 can slide vertically an enlarged portion 49 of a plunger rod 51. Extending inwardly into its bore from said

sleeve 24 is a helical rib 52 which fits snugly in a helical groove 53 in said enlarged portion 49. Said enlarged portion 49 is also formed with vertically extending grooves 56 in which fit ribs 54 extending vertically and 70 inwardly from the upper head 23.

Said upper head, being screwed to the casing 19, which is connected to the hinge leaf 1, does not turn, and, consequently, said plunger rod 51 cannot turn on account of 75 the ribs 54 fitting in the vertically extending grooves 56 therein. It can, however, slide in said head. It is caused to so slide by the rotary motion of the rib 52 in the helical non-rotary groove 53, said rib 52 partaking 80 of this rotary motion with the sleeve 24 and upper spring housing 32, which is secured by the screw 34 to the rounded extension 36 of the hinge leaf 3. Thus, when the door swings outwardly on its hinges, the 85 sleeve 24 also turns and the rib 52 turns about the axis of the plunger rod, producing an upward motion of said plunger rod.

The downward movement of said plunger rod 51, when the door is closing caused by 90 the co-action of said rib 52 and helical groove 53, is assisted by a spring 57 coiled around the rod 51, the ends of which spring 95 abut respectively against the upper head 23 and a plunger 58. This movement forces liquid from the lower portion of the plunger chamber, below a plunger 58 through a channel 59 in a lateral extension or enlargement 60 of the casing 19. An upper portion 100 61 of said channel is enlarged and communicates with the upper portion of a liquid chamber 65 within the casing 19 by a passage 68. But said enlarged passage 61 is almost closed by a pin 63 which is held down by a screw 64 screwed in said enlargement 105 60, a washer 66 being interposed between the lower end of said screw and the upper end of said pin. The lower end of said pin is slotted, as shown at 67, so as to permit liquid to pass therethrough only slowly. A 110 packing ring 66' is contained in an annular groove in the side of the plunger 58.

A second passage 62 is also provided, leading from the channel 59 to an upper portion of the liquid chamber. The plunger 58, 115 however, does not ordinarily pass said second passage on its downward movement. A second socket 37', (Fig. 4) is, however, provided in the housing 32, and, when said housing is moved relatively to the cylindrical extension 36 so as to bring said second socket 37' into register with said screw 34, and said screw 34 has entered said second socket 37', then the magnitude of the angular rotation of the sleeve 24 is increased and the 120 vertical movement of the piston rod is also increased, so that, near the end of its movement corresponding to the closure of the door, the piston passes said second passage; and, in that case, liquid flows, not only by 125 130

the passage 68 but also by the passage 62, and, therefore, escapes more rapidly than before and the door closes at increased speed.

The plunger offers practically no resistance to the opening of the door, for, when it is moving upwardly, the liquid moves freely through an opening 69 in the plunger, which opening, on the downward movement of the plunger, is closed automatically by a ball valve 70.

To prevent breaking of parts due to great force being ignorantly or otherwise exerted to close the door more rapidly than it is automatically closed, there is provided, in the plunger 58, an upwardly opening valve 72 closing a passage therethrough and having a valve stem 73 around which is a coiled spring 74 in a recess in the under side of the plunger and compressed between said piston and a washer 76 secured on the lower end of the valve stem, having fluid passages 77 in its edges.

Fig. 3^a illustrates the mode of application of my invention to a door swinging both ways. In this case, two check-hinges are provided, one on each side of the door, the hinge leaf which is ordinarily attached to the edge of the door being common to both check-hinges, as shown at 78, the other hinge leaf to one check-hinge being attached, as before, to the door jamb, and of the other check-hinge being attached to the hinged edge of the door.

In the inner surface of the sleeve 24 is a vertically extending groove 71 in which is placed a sufficient amount of lubricating material to maintain the inner surface of said sleeve well lubricated to permit the plunger rod to slide freely therein.

The upper end of said plunger rod is formed with a central passage 81, which, as shown at 82, opens in the bottom of one of the vertically extending grooves 57 where crossed by the helical groove 53. By means of this passage 81 the liquid chamber 65 can be filled with liquid.

The downward movement of the plunger rod is limited by the abutment against the upper flaring end of the sleeve 24 of a leather washer 83 on which is a metal washer 84, both surrounding a reduced portion of the plunger rod and retained in place by a nut 86 screwed on the threaded upper end of said reduced portion.

In the spring housing 13 and in the lower end of the casing 19 are apertures, and in the lower head 21 is a socket, all registering with each other and in the cavity thus formed is screwed a casing 88 in which is a compressed coiled spring 89, which presses

against a rounded pin 91 slidable in said cavity, which pin slides through the contracted rear end of the casing, but has a head 93 outside the casing and in the cavity, and which pin 91, can when the door is open 65 to a certain extent, enter a hole 92 in the lower part of the extension 36, thus retaining the door in the open position. When it is not desired to use the pin 91, the casing 88 can be screwed into the cavity a sufficient 70 distance so that the pin no longer projects a sufficient distance to be operative.

I claim:—

1. The combination of a fluid chamber, a hinge leaf attached thereto, a spring housing 75 secured to one end of said chamber, a cap rotatable in the housing, a spring coiled about said cap having its ends attached respectively to said cap and to said housing, a companion hinge leaf of which one end is 80 secured to said cap, a device secured to the other end of said latter hinge leaf, a spring housing rotatable about said second-named cap and also rotatable relative to said fluid chamber, a coiled spring within said last- 85 named spring housing, of which one end is secured to said last-named spring housing, and the other to said last-named cap, and means in said fluid chamber for controlling the turning of said hinge leaves relative to 90 each other.

2. The combination of a fluid chamber, spring housings at the ends of said chamber, caps rotatable relative to the housings, coiled 95 springs in the housings having their ends attached respectively to said caps and to said housing, hinge leaves rotatable with the respective ends of the springs, and means in said fluid chamber for controlling the speed of turning of said hinge leaves relative to 100 each other.

3. The combination of a hinge leaf, a fluid chamber secured thereto, upper and lower heads therefor, a spring housing secured to the lower head, a cap rotatable in said 105 housing, a clock spring in said housing, and attached at its ends to said cap and housing, a companion hinge leaf secured to said cap, a sleeve rotatable relative to said upper head, a housing attached to said sleeve, a cap rotatable in said latter housing, a supplementary hinge leaf adapted to be hinged to the same element as the first-named hinge leaf, means for adjustably securing said supplementary hinge leaf to said last-named cap, 110 and means in said fluid chamber for controlling the turning movement of said hinge leaves relative to each other.

EMILE FRANCKAERTS.
